UNITED STATES PATENT OFFICE

138,216

DESIGN FOR A GEARBOX FOR AIRCRAFT ENGINE STARTERS

Romeo M. Nardone, Westwood, N. J., assignor to
Bendix Aviation Corporation, Bendix, N. J., a
corporation of Delaware

Application June 15, 1943, Serial No. 110,461

Term of patent 14 years

(Cl. D71—1)

To all whom it may concern:

Be it known that I, Romeo M. Nardone, a citizen of the United States, residing in Westwood, in the county of Bergen, and State of New Jersey, have invented a new, original, and ornamental Design for a Gearbox for Aircraft Engine Starters, of which the following is a specification, reference being had to the accompanying drawings, forming part thereof.

In the drawings:

Fig. 1 is a perspective view of a gearbox for

aircraft engine starters showing my new design as it appears when viewed from an angle between the front and side thereof;

Fig. 2 is a front elevational view of the device illustrated in Fig. 1;

Fig. 3 is a top plan view of said device; and
Fig. 4 is a rear elevational view of said device.

I claim:

The ornamental design for a gearbox for aircraft engine starters, as shown.

ROMEON M. NARDONE.
